UNITED STATES PATENT OFFICE.

JAMES TREGURTHA, OF MALDEN, ASSIGNOR, BY MESNE ASSIGNMENTS, TO
THE ADJUSTABLE TELEPHONE SUPPORT COMPANY, OF BOSTON, MASS.

SUPPORT FOR TELEPHONES.

SPECIFICATION forming part of Letters Patent No. 289,179, dated November 27, 1883.

Application filed March 26, 1883. (No model.)

To all whom it may concern:

Be it known that I, JAMES TREGURTHA, of 5
Malden, in the county of Middlesex and State
of Massachusetts, have invented certain new
and useful Improvements in Supports or
Stands for Telephonic or other Instruments,
of which the following is a full, clear, and ex-
act description.

This invention relates to a stand or support,
more particularly designed for telephonic in-
struments, transmitters, and receivers, either
one or both, although it is also applicable to
microscopic and other instruments.

The object of the invention is to provide a
stand or support for such instruments, which
shall be capable of ready and easy adjustment
in position for the convenient use of either or
both by operators. The present improved
stand or support is composed in substance of
20 clamps or other holders, one for the trans-
mitter and one for the receiver, each doubly
jointed for being swung on separate centers,
in planes at an angle to each other, to one end
of separate telescoping arms, each of which
25 arms at its other end is doubly jointed for be-
ing swung on separate centers, in planes at an
angle to each other, to separate ends of a com-
mon standard or rod or to separate standards
or rods arranged to be adjusted as to its or
30 their distance from, and otherwise to be
swung in relation to the location of the fix-
ture to which this improved stand is attached
for the use of the telephonic instruments car-
ried by it, all substantially as hereinafter de-
35 scribed.

In the accompanying plates of drawings is
illustrated a support or stand of the present
improved construction.

In Plate 1, Figure 1 is a front elevation,
40 showing the improved stand or support as
secured to a table or bench, and the trans-
mitter at the right and the receiver at the left, in
which position in use, with the mouth of the
operator at the transmitter, the receiver would
45 be at the left ear. Fig. 2 is an elevation at
the right-hand side of the stand or support in
the position of Fig. 1. Fig. 3 is a plan view
of the stand or support in the position of Fig.
2. Fig. 4 is a detail sectional view, enlarged,
50 on line 4 4, Fig. 2. Fig. 5 is a detail horizon-

tal sectional view on line 5 5, Fig. 4. In
Plate 2, Fig. 6 is a perspective view of the
support in the position shown in Fig. 1. Fig.
7 is a face view. Fig. 8 is a horizontal sec-
tion on line 8 8, Fig. 6. Fig. 9 is a vertical 55
section on line 9 9, Fig. 6; and Fig. 10 is a
horizontal section on line 10 10, Fig. 9, each
and all in detail and enlarged.

In the drawings, A represents a base-plate,
to be secured to a table or bench, B, or other 60
suitable fixture with screws or other suitable
fastening means.

C is a tubular standard rising from the base
plate A, and containing a vertical screw-threaded
65 tubular rod, D, having a screw-threaded
nut, E, which, being turned upon the screw-rod
D, either to the right or to the left, will cause
said rod to move up or down, said nut being
confined against vertical movement by and
between the upper and lower bracket-arms, F 70
G, of the standard C, and the rod D held against
turning, while it is left free to so move up and
down, as the case may be, by a spline-joint be-
tween it and the bracket-arm, said spline-
joint consisting of the horizontal pin *a* on 75
said arm and the vertical groove *b* in said
screw-rod.

H is a horizontal plate or disk fixed to the
upper end of the tubular screw-rod D. This
fixed plate H on its upper face has a circular 80
recess or depression, *d*, receiving a circular
washer, *e*, of leather or other suitable packing
material, and above this washer is a hori-
zontal circular and rotating disk, J, which is con-
centric with screw-rod D, and is concentrically 85
attached to the lower end of a vertical tubular
rod, K, and is confined against said washer
e and said fixed plate H by a ring, L, secured
by means of screws *f*, or otherwise, to the
plate H outside of the washer. This ring L is 90
of a shape to overlap the upper face of the mov-
ing disk J at and around its outer edge, and it
has a circular concentric groove, *g*, in its face,
in contact with said rotating disk J. This
groove *g* has a fixed pin or abutment, *h*, and 95
it also receives a pin or abutment, *k*, of the
rotating disk J, all so that said disk J is free
to be turned or rotated in either direction up-
on the stationary plate H of the standard C,
but not in either direction for a complete turn 100

or rotation, because of the necessary abutment of the pin h of the disk J against the pin h of the ring L , that is attached, as described, to the plate H , carried by the adjustable screw-rod 5 D of the standard C . The fixed plate H , rotating disk J , and washer e all are open at their center, corresponding to the opening of the tubular screw-rod D and the upward-extending rod K , from the rotating disk J , and 10 by tightening or loosening the contact of the rotating disk against said washer and fixed plate, it is plain the ease with which the rotating disk may be turned or rotated, can be regulated at pleasure, and as a consequence, 15 while the same may be made to be freely adjustable, yet it can be made secure against accidental displacement. The upward-extending tubular rod K , attached to and traveling around with the rotating disk J , is at a short 20 distance above said disk bent and brought into a horizontal position, as shown at M , and this horizontal part or extension terminates at the outer end in a vertical collar, N , in which is fixed a vertical rod or standard, O , extending 25 equally above and below said horizontal extension. The tubular rod K is also tubular in its horizontal extension M , and, in fact, for its whole length, opening at l to the outside of the vertical collar N , in which the vertical 30 standard-rod O is fixed, as above described. This rod-standard O supports both a telephonic transmitter, P , and a telephonic receiver, Q , either of any of the usual or suitable constructions. This support of the transmitter and receiver is in each case through similar mechanism, and such being the case, a description of the mechanism of one obviously is sufficient if the proper letters be applied to the corresponding parts of the other.

40 The transmitter P is connected to and supported from the lower end, and the receiver Q is connected to and supported from the upper end, of the rod-standard O , and the connecting and supporting mechanism of each is 45 as follows: Four joints, R , S , T , and U , all of similar construction, a telescoping rod, V , and a clamp or holder, W , each of which parts is duplicated for each telephonic instrument, transmitter P , and receiver Q . Each joint R , 50 S , T , and U is in three separate lifts or leaves, m n q , of a circular disk shape, and severally placed by their flat surfaces upon each other with a washer, r , (see Figs. 4 and 5 more particularly,) of leather or other suitable packing material, between them, and all secured together 55 by a headed screw-bolt, t , passing concentrically through their several thicknesses and screwing into either one or both of the outer lifts or disks, m q , but loosely through the middle lift or disk, n , which is thus made capable, if not bound to the disks at each side thereof by sufficiently screwing up the axial screw-bolt, of being turned or rotated upon said axial bolt. The outside disks, m and q , of each of said 60 joints are locked together by a pin, a^2 , fastened to one and entering loosely into a socket, b^2 , of the other, and located in a lug, d^2 , of each disk,

which lugs project from the edge and one side of the disks, and, as a consequence, with either of said outside disks fastened or held against turning in any manner, the other one thereof will be correspondingly held against movement; but if neither thereof is so fastened and otherwise they are free to be turned—that is, if not bound against the sides of the middle 75 disk, n , by means of the center or axial bolt, t , or either of them held in any other way—then they, with said axial bolt, can be rotated, turning by said bolt within the center opening and by the inner face of each outside disk 80 against the opposite faces of the middle disk. The duplicate joints R are secured one to the upper end and the other to the lower end of the rod-standard O , and in each case the several disks making each joint are horizontal 85 and fastened to or against the ends of said standard by entering and securing the axial bolt t of each into the same, and, in fact, preferably the outside disk of each joint against the ends of said standard is rigidly and independently attached thereto. The middle disk of the upper joint has an angular and radial arm, e^2 , connecting it to an outer disk, q , of the duplicate joints S , next in order of arrangement from the rod-standard O , the middle 90 disk, n , of each of which joints is carried by one of the separate and duplicate telescopic rods V . Both telescopic rods V project radially from the axis of rotation of their respective joints, and each is composed of an outer tubular rod, h^2 , having within it another rod, k^2 , both of which make the telescoping-rod—that is, a rod capable of being lengthened and shortened—either by drawing the inner one, k^2 , out of and forcing it into the 95 outer one, h^2 , or by drawing the outer one, h^2 , off and forcing it over the inner one, k^2 . Each joint R rotates in a horizontal plane, and each joint S in a vertical plane, and said planes of rotation are at right angles. 100

One and the outer end of the inner rod, k^2 , of each telescoping rod V carries a middle disk, n , radially attached, of one of the duplicate joints T , next in order of arrangement from the standard-rod O , and one of the outside disks, m , of each of said joints has a right-angular and radial arm, l^2 , connecting it to the middle disk, n , of one of the duplicate joints U , and the next and last in the order of arrangement from the standard-rod O . To the 110 outside disk, m , of each of said joints U , the farther removed from the axis of rotation of the joints T , is secured one of the duplicate clamps or holders W . These clamps are each of any suitable construction—for instance, the one, a ring, X , divided into two halves, secured together about the body of the receiver Q , and the other a bracket, Y , attached by screws to the under side of the transmitter P . Each joint T and each joint U rotates in a 115 plane at right angles to the other, and the rotation of the former is in a plane coincident with the longitudinal axis of the telescopic rod V , to which it is connected. 120

125

The pin a^2 , locking together the two outside disks of each of the joints R S T U, as herein described, prevents, by the abutment against it on either side of a part—to wit, the 5 angular arm-extensions $e^2 l^2$, or the telescopic rods V, attached to or forming a part of and moving with the middle disk of such joint—or by its abutment against said part of the middle disk, any of said joints from having or making 10 a complete turn or rotation in either direction about or upon their respective axial bolts or pintles t.

The freedom with which each of the several 15 joints R S T U may work or be worked, it is obvious, can be regulated by tightening up or loosening its axial bolt t, or, in other words, by tightening or loosening the several disks of each joint in their bearing against each other, and plainly any of the joints may be made 20 rigid or fast at pleasure by simply screwing up its axial bolt t sufficiently therefor.

Electric wire connections are made with 25 each of the telephonic instruments, transmitter P, and receiver Q, as usual, and in making these connections the several wires pass from the instruments to and through the open end l of the horizontal tubular rod M, and thence through said rod, the rotating disk J carrying it, standard C, hollow screw-rod D, 30 and base-plate A to the other necessary parts to be connected.

In the improved stand or support for telephonic instruments, and attached to a table or bench, B, as herein described, it is plain that 35 each of the instruments is capable of being adjusted in height or distance from the table—first, by raising or lowering the vertical screw-rod D in the standard C from the turning of the screw-nut E; second, by swinging its telescopic rod V in a vertical direction through the 40 joint S of said rod V, which is connected with the middle disk, n, of the joint R upon the rod-standard O; third, by swinging its clamp W in a vertical direction or plane through the 45 joint U of said clamp, which is connected with one of the outside disks, m, of the joint T at the outer end of its telescopic rod V; and, fourth, by either lengthening or shortening its telescopic arm or rod V; and, again, each of 50 the instruments is capable of being adjusted in its distance from a given vertical plane passing from the front to the rear, or passing across and between the front and the rear of the support herein described, as it is attached to the 55 table or bench B—first, by rotating the disk J upon its support of the base-plate standard C; second, by swinging its telescopic arm or rod V in a vertical plane or direction through the joint S of said rod, connecting it with the middle disk of the joint R upon the rod-standard O; third, by swinging its telescopic arm or rod V in a horizontal direction or plane through its joint R, connecting it with the rod-standard O; fourth, by swinging its clamp or holder 60 W in a vertical direction or plane through the joint T upon the outer end of its telescopic rod V; fifth, by swinging its clamp or holder 65

W around upon its joint U, which joint is connected to the joint T, connected to the outer end of the telescoping arm V; sixth, by either 70 lengthening or shortening its telescoping arm or rod V.

The adjustments of either telephonic instrument as hereinabove described, except as to those made by the operation of the screw-nut 75 E and the rotating disk J, are independent of and separate and distinct from each other, and from the variety of the same, as appears from the recital thereof herein given, together with the adjustment secured from the operation of 80 said screw-nut E and said rotating disk, it is obvious that either instrument is capable of being placed in almost any conceivable position, (of course within given limits,) either as to any given vertical or horizontal plane, or 85 as to the other or companion instrument upon the same stand or support, and therefore, as a consequence, either and both instruments can be located for most convenient, easy, and ready use, and to suit the position and condition 90 of any operator or operators, and with the utmost ease, facility, and quickness, the advantages of all of which are obvious. Limiting the rotations of the disk J and of the separate joints R S T U, substantially as described, 95 constituting, with other parts, the stand or support of this invention, prevents all possibility of twisting or winding of the electric wires leading to and from the instruments upon any part or parts of the stand or support to an 100 extent to injure or damage the same, or to interfere with their proper operation at all times.

A screw-nut, E, for adjusting the screw-rod D, and operating thereon as described, together with a telephonic instrument or instruments connected to said rod, is important, in that it not only by a turning of the screw-nut in the proper direction secures the lifting and lowering of the instruments through its operation upon said screw-rod, but it also holds 105 said instruments in their so adjusted position without further operation of any mechanism or use of any other fastening device or devices.

The horizontal extension M and the vertical rod K, to which it forms such extension, and 110 also both the upper and lower parts of the rod-standard O, may each and all, or such of them as desired, be made telescoping the same as described for the telescoping rods V, and each arm or rod or part so telescoped may be 115 allowed to turn freely upon the other, or be constructed with a spline-joint, as at m², Fig. 1, to prevent them from so turning.

It is obvious, first, that the stand or support herein described, as to either instrument, 125 is complete of itself, and works the same in every respect; second, that while either instrument can be placed at a greater or less distance or height from the table or other support to which the telephonic stand is secured, 130 and also can be swung about the usual line of the movement or adjustment just above stated—that is, the vertical axis of the standard B—either instrument is also capable of being

swung around two other axes (the axes of the joints R U) at a distance from each other, both of which axes are parallel to each other, and also to but not coincident with the axial swing 5 and adjustment of the instrument first above stated, and, in addition thereto, either instrument is also capable of being swung around two other axes (the axes of the joints S T) at a distance from and parallel to each other, 10 and at right angles to each and all the other axes above referred to.

Among special advantages of the telephone stand or support of this invention, in addition to its general and other capabilities before recited, it may be well to mention, first, that the telephonic instruments and their connections, when not in use, can be swung to the rear or either side of the standard B, and thus placed out of the way; second, that the double joints of the telescoping rods at each end, as described, are in the nature of universal joints, and as a consequence in whatever positions the instruments may be placed by swinging them upon said joints and otherwise adjusting them, a then slight movement of the joints enables the instruments to be placed squarely to the mouth or ear, as the case may be, and without necessarily changing the height or distance of the whole apparatus for 30 its point of fixture to the table, wall, &c.; third, as the instruments are at the outer ends of their respective carrying-arms and jointed thereto, as described, when placed in position for use there are no obstructing arms in the 35 way of the operator, and, again, the instruments can be swung and placed under the carrying-arms, so as to leave a clear space below; fourth, by a simple movement of the parts carrying the instruments the position 40 of the instruments can be readily changed for the receiver to be used at either the right or left ear of the operator, and for the transmitter to be placed in suitable relative position.

The washers for the working-joints, herein 45 described, may be dispensed with; but they are desirable, as they enable sufficient friction to be given to the working-faces of the joints to hold the joints against accidental working and without tightening the parts together to 50 an extent to prevent their being easily worked.

The telescoping of the rods may be dispensed with; but it is best to so make them. The carrying-arm for either instrument may be doubly jointed, as described, only at one 55 and either end, instead of at both ends. The double jointing of the carrying-arm for either instrument may be used in connection with means for elevating and lowering their carrying-arm other than the screw-rod D and screw- 60 nut E. The means for elevating and lowering the stand or support—to wit, the screw-rod D and screw-nut E—may be used with other means of connection of the instruments therewith. The standard C may be secured 65 to the wall of a room, &c., in lieu of a table, and such standard may be of other forms—as, for instance, if it is to be attached to a wall in

the form of a bracket, arranged to swing upon the wall—and other obvious changes and combinations of the several parts which have 70 been herein described so fully may be made, and yet secure more or less of the results aimed at by the present invention. However, a telephone stand or support having all the parts and operations and movements specified is 75 most desirable, for manifest reasons.

In conclusion, it will be observed that although the present improved stand or holder has been herein particularly described in connection with telephonic instruments, and in 80 the claims also particularly so stated, such description and claims are meant to and do include any and all other instruments for which said stand or support may be found available—as, for instance, microscopic instruments, &c.—and so, therefore, it is not intended that this invention, either in its description or in the recital of the claims shall be limited to telephonic instruments only.

Having thus described my invention, what 90 I claim, and desire to secure by Letters Patent, is—

1. The combination, in a stand or support for telephonic instruments, &c., having a clamp or holder, W, for an instrument and a 95 standard, C, of a screw-rod, D, carrying said clamp, and a screw-nut, E, arranged to operate said rod, substantially as described, for the purpose specified.

2. In a stand or support for telephonic instruments, &c., an arm or support carrying an instrument and attached to a screw-rod, D, to be swung thereon, in combination with a standard, C, and screw-nut E, for raising and lowering said screw-rod, substantially as and 105 for the purposes described.

3. In a stand or support for telephonic instruments, &c., a clamp or holder, W, for an instrument jointed to an arm to be swung thereon in intersecting or crossing planes, in 110 combination with a standard, C, carrying screw-nut E and screw-rod D, connected to said arm, substantially as and for the purpose described.

4. In a stand or support for telephonic instruments, &c., a clamp or holder, W, for an instrument jointed to an arm to be swung thereon in intersecting or crossing planes, in combination with a standard, C, fixed to a suitable support and provided with a screw- 120 nut, E, and screw-rod D, connecting said arm to said support and constructed and arranged for said arm to be adjusted and also to be swung upon said screw-rod D, substantially as and for the purpose described.

5. In a stand or support for telephonic instruments, &c., a clamp or holder, W, for an instrument jointed to an arm, V, to be swung thereon in intersecting or crossing planes, and which arm is jointed to an arm, M, to be swung 130 thereon in intersecting or crossing planes, in combination with a standard, C, fixed to a suitable support, and to which standard said arm M is connected for adjustment relative

thereto and to said support, substantially as and for the purpose described.

6. In a stand or support for telephonic instruments, &c., a clamp or holder, W, for an instrument, an arm, V, jointed to said holder for said holder to be swung thereon in intersecting or crossing planes, and also similarly jointed to an arm, M, in combination with a standard, C, fixed to a suitable support and 5 provided with a screw-nut, E, and a screw-rod, D, connecting said arm to said support, and constructed and arranged for said arm to be adjusted and also to be swung about the axis of said screw nut and rod, substantially 10 as and for the purpose described.
7. In a stand or support for telephonic instruments, &c., a clamp or holder, W, for an instrument jointed to an arm, V, to be swung thereon in intersecting or crossing planes, and 15 which arm is constructed to be lengthened and shortened, in combination with a standard, C, fixed to a suitable support, and to which standard said arm V is connected for a movement thereon, substantially as and for the purpose described.

8. In a stand or support for telephonic instruments, &c., a clamp or holder, W, for an instrument and a standard, in combination with an arm, V, which is arranged between them and connects them, and jointed with 20 angular joints R S T U, composed of lifts *m n q*, and an axial pintle, t, and connecting-arm M, substantially as described, for the purpose specified.

9. A stand or support for telephonic instruments, &c., composed of a clamp or holder, W, joints U and T, rod V, joints S and R, arm M, swinging upon standard C, screw-rod D, and screw-nut E, constructed, arranged, and combined together, substantially as described, for 25 the purpose specified.

In testimony whereof I have hereunto set my hand in the presence of two subscribing witnesses.

JAMES TREGURTHA.
